[57] CLAIM

The ornamental design for a telephone answering unit, substantially as shown.

DESCRIPTION

FIG. 1 is a perspective view of my new design taken from the front and to one side, with the cover closed; FIG. 2 is a bottom plan view of my design; FIG. 3 is a rear view of my design; and FIG. 4 is a perspective view of my design like FIG. 1, but with the cover open.

FIG. 2FIG. 3FIG. 1
